G. DINKELA

MEANS FOR PREVENTING SELF IGNITION OF AIRSHIPS AND THE LIKE

Filed Jan. 5, 1922

FIG. 1

FIG. 2

FIG. 3

Inventor:

G. Dinkela

By *Lawrence Langner*
Attorney

UNITED STATES PATENT OFFICE.

GOTTLIEB DINKELA, OF CHARLOTTENBURG, NEAR BERLIN, GERMANY.

MEANS FOR PREVENTING SELF-IGNITION OF AIRSHIPS AND THE LIKE.

Application filed January 5, 1922. Serial No. 527,167.

To all whom it may concern:

Be it known that I, GOTTLIEB DINKELA, a citizen of the German Republic, residing at 16, Kuno Fischerstrasse, Charlottenburg 5 near Berlin, Germany, have invented certain new and useful Improvements in Means for Preventing Self-Ignition of Airships and the like, of which the following is a specification.

- 10 The subject of the present invention is an arrangement for preventing self-ignition such as occurs in rapidly ascending airships. Such self-ignition is due to the electrical charging and discharging of the condensate. An airship, filled with a gas at about the temperature of the atmosphere at the earth's level, rises quickly into high, cold strata producing rapid condensation of the moisture in the gas.
- 15 Between 10° C. to 30° C. the number of degrees of heat corresponds approximately to the number of grammes of water contained in a cubic metre of fully saturated gas. As the gas in the container is in continuous contact with the moisture, i. e., is fully saturated, a modern airship of, for example 60,000 cubic metres filled at 30° C. absorbs with the air $60,000 \times 30 = 1,800,000$ grammes or 1,800 kilogrammes of moisture.
- 20 This moisture almost completely condenses on the gas becoming cooled to 0° C.

Under normal conditions there are now contained in the air or in the gas 1,250 positive and 1,000 negative ions per cubic metre, the former of which form condensation zones. From Slaby's experiments increase of the tension in the drops of moisture forming is inversely proportional to the difference between the size of the new 25 surface formed on the conjunction of two equally large bubbles of moisture and of the sum of the surfaces of the original bubbles. The charge distributed over a large space at the earth's surface is thus condensed within the drops of moisture and increases in tension the greater the diameter of the drops (c. f. large rain drops). The normal electrical field amounts at sea level to about 150 volts; at a height of one kilometre 30 it amounts only on the average to about 25 volts; at a height of 6 kilometres it will be only about 8 volts and at the highest the sum of the voltages amounts to 200 kilovolts at a height of 10 kilometres (according to Toepler).

The air ship having a comparatively high

tension at the earth's surface ascends to higher strata of air where the electrical field is weaker and exceedingly high tensions are developed on the drops of moisture by condensation, the difference between the tensions within the airship and the weaker field of the surrounding atmosphere resulting in discharges into the surrounding electrical field, these discharges either being partial discharges or total discharges forming fatal sparks. Thus it happens that many airships suddenly burst into flames.

The present invention has for its object to bring the potential of the ship as rapidly as possible to that of its surroundings and thus to keep the potential difference within the smallest limits.

In order that the invention may be clearly understood, reference will be made to the accompanying drawing, in which the subject of the invention is applied by way of example to a rigid metal airship, e. g. a ship of the Zeppelin-type, and in which Fig. 1 is a front view and Fig. 2 a side view, while Fig. 3 is a section through one of the cells.

The airship illustrated in the drawing consists of the internal metallic body *c*, containing a series of cells *a* for the hydrogen gas, only one of which, however, is shown. Each cell *a* is provided in its lower part with an electrically conducting net-work *b* while on the outer surface of the envelope *f*, surrounding the metallic body *c* a second electrically conducting net-work *d* carrying a system of radiating points *e* is arranged. The net-work *b* and the system of radiating points *e* are in electrical connection, for instance by the intermediary of the metallic body *c* of the airship.

With wooden airship bodies only the outer net-work is provided.

The condensed moisture from the gas falls on the walls of the cell *a* giving its electrical charge thereto, which is accumulated by the net-work *b* in the lower part of each cell, from where the electricity is conducted by the intermediary of the metallic body *c* to the system of radiating points *e*, carried by the outer net-work *d* mounted externally on the envelope *f*.

By the arrangement described the electrical charge of the condensate is discharged, not as hitherto in uncontrollable partial discharges nor in total discharges into space

producing sparks, but to the system of radiating points and therefrom gradually and therefore safely into space.

What I claim is:

- 5 In means for preventing self-ignition of airships the combination of an electrically conducting net-work arranged in the lower part of the gas-containers and adapted to accumulate the electricity transmitted by
- 10 the water drops formed by the condensation of the moisture of the filling medium of the airship, a system of points arranged on the

external surfaces of the envelope and adapted to radiate the electricity into the space and means adapted to electrically connect 15 the said net-work in the gas containers with the said system of points.

In testimony whereof I affix my signature in presence of two witnesses.

GOTTLIEB DINKELA.
